Harold D. Penney, ATTORNEY.

UNITED STATES PATENT OFFICE

EDWIN G. BLACKWELL, OF NEW YORK, N. Y.

RETORT STRUCTURE

Application filed September 22, 1927. Serial No. 221,243.

This invention relates to retorts or chambers and more particularly to retorts for the carbonization of coal in gas manufacture though it is noted that the invention is not limited to retorts or heating chambers, and the word "retort" as herein used covers chambers for other purposes.

My present invention is directed to an improved form of retort for the manufacture 10 of gas by the carbonization of coal, and has to do, specifically, with the details of building the retort proper, in single or plural combinations, for eliminating faults at present existing in such retorts, as at present constructed.

15 In plants, for the carbonization of coal and other materials, comprising retorts or ovens of vertical, inclined or horizontal types the material undergoing treatment may expand during carbonization or upon the application of heat and exert an outward bursting stress on the retort walls. The heat applied may be either by conduction through the retort or oven walls or by internal heating arrangements, or by a combination of the two.

25 One object of the invention is to provide a wall for a chamber of this kind which will resist outwardly directed stresses.

Another object of the invention is to provide a wall of this kind which will resist 30 either outward or inward pressure.

Another object of the invention is to provide a wall of this kind having courses respectively for outward and inward pressure.

Other objects of the invention are to improve 35 generally the simplicity and efficiency of such walls and to provide a wall of this kind which is durable and reliable in operation, and economical to construct.

Still other objects of the invention will 40 appear as the description proceeds; and while herein details of the invention are described and claimed, the invention is not limited to these, since many and various changes may be made without departing from the scope of the 45 invention as claimed in the broader claims.

While herein the inside of the retort is shown as approximating an ellipse rather than rectangular or other shapes, and the brick walls are in sections rather than solid 50 rings and have plain rather than tongue and

groove connections it is noted that the invention is not concerned with or limited to these details.

The present invention contemplates the building of the oven or retort walls of arch 55 like construction with the top or back of the arch against the contained material in such manner as to resist the bursting stress, which in retorts or ovens of present construction has had the tendency to either distort the 60 retort or oven shape or to actually dislocate individual sections of the material entering into the retort or oven construction.

The inventive features for the accomplishment 65 of these and other objects are shown herein in connection with an improved retort which, briefly stated, includes opposed abutment members having abutment faces between which is disposed a retort comprising elongated courses of brick including end 70 bricks disposed against said abutment faces, the side brick of courses being laid end-for-end to provide end abutment faces, all of said abutment faces converging in the direction of the forces acting on the retort side wall. 75

Inasmuch as retorts of this general nature are usually similar, as to the arrangement of setting, flues and retort proper, I have only disclosed sufficient structure herein to illustrate my improvement and the underlying 80 functions and advantages thereof.

In the accompanying drawing showing, by way of example, one of many possible embodiments of the invention,

Fig. 1 is a fragmentary side elevation of 85 my retort structure;

Figs. 2 to 4 are horizontal sectional views taken respectively on the lines 2-2, 3-3 and 4-4 of Fig. 1 looking in the direction of 90 the arrows;

Fig. 5 is a diagrammatic view illustrating the manner in which my structure opposes certain forces; and Fig. 6 is a fragmentary view showing the angles of the abutment faces.

My improved retort or chamber 10 is here- 95 in shown in combination, with opposite walls 11 (Fig. 2) of a plant against which are disposed abutment members such as opposed wall tiles 12 disposed against said opposite 100

walls, parallel to each other. If the retort is vertical these tiles are vertical but are horizontal or inclined if the retort 10 is horizontal or inclined. The opposing face 5 of each tile is longitudinally divided at its middle axis 15 into a pair of immovable abutment faces 16 slightly inwardly converging toward the rear face or main plane of the tile.

The retort 10 is between said walls and 10 comprises elongated approximately elliptical courses 17, 18 and 19 of refractory brick staggered relative to the brick of the adjacent course and laid in planes transverse to said tiles, with the end bricks disposed flat 15 against said abutment faces 16.

Each alternate course 18 (Fig. 2) comprises a central end brick 20 having inclined meeting faces meeting at said axis 15 and lying flat against said abutment faces 16, 20 and corner bricks 21 adjacent to said central brick and having flat faces contacting and extending to the outer side edges 22 of said abutment faces 16.

The intervening courses 19 (Fig. 3) comprise corner brick 25 meeting above the center of the brick 20 at said axis 15 and having flat faces extending to said edges 22.

The outer face of each corner brick may be provided with a recess 26, 27 to increase 30 the lightness and heat-conductivity of the brick.

The side brick, 30, 31 of all the courses are laid end-for-end between said corner brick and all have end abutment faces 33 engaging 35 adjacent side brick and said corner bricks. All of said abutment faces 16 and 33 lie substantially in imaginary converging planes 34 (Fig. 6) all radial to a remote imaginary line parallel to and equidistant from said 40 tiles on the side of the retort side-wall toward which the forces indicated by the arrows 35 (Fig. 5), acting on the wall tend to push said side wall. In this way said corner and side bricks all act as a keystone and tend to 45 wedge, with forces represented by the arrows 36, against adjacent brick or said tile to prevent the retort wall or any brick from being displaced by said forces.

While herein the tiles 12 are shown as 50 mounted against the walls 11, and only one retort is shown between the walls 11, rather than two or more retorts placed end to end, as in usual construction, it is understood that the invention is not thus limited.

Where division walls or floor tiles support the retort and themselves resist outward bursting forces and in turn exert an inward bursting face, the above described courses 18 and 19 serve to resist these inward forces, 60 since the outer and inner faces of the side and corner brick 21, 25, 30, 31 converge toward the center of each side of the course, the corner brick forming wide bases abutting the face 16 of the wall tile, whereby the 65 main axes of all the side brick 30, 31 of each

retort side wall all lie in a plane passing through said bases and the associated abutment face 16, of the wall tiles, whereby the bricks of the side wall, because of the friction therebetween tend to wedge whenever 70 the retort wall is pushed from one side or the other.

If desired, however, I may use the construction of the course 17 (Fig. 4) for resisting this inward force, in which construction the abutment faces 16' are not so wide as the faces 16, and the corner bricks 21' disposed against said abutment faces are not so wide as the brick 21. In this form, the forces to be overcome are from the outside 75 and the abutment faces 16' and 33' converge inwardly, which is in the direction of the outside forces acting on the retort side wall.

While the drawings do not so disclose it, they being of a somewhat conventional, diagrammatic showing, it is understood that in the usual customary practice of erection of these herein described retorts, that the bricks forming the completed retort are cemented or bonded together by a suitable fire-proof 85 bond, in the usual manner.

I claim as my invention:

1. In combination with spaced vertical walls, a retort abutting said walls comprising courses of fire abutting bricks laid in planes transverse to said walls including vertical planes of contact between each of said bricks and bricks contiguous thereto, the vertical planes of contact of said bricks on two opposite sides of each brick converging toward the exterior of said retort.

2. In combination with opposed spaced walls, a vertical retort abutting said walls comprising a plurality of courses of bricks laid in planes transverse to the vertical axis 105 of said retort having vertical planes of contact between each of the bricks and bricks contiguous thereto, the vertical planes of contact of said bricks on two opposite sides of each brick being converged towards the 110 exterior of said retort.

3. In combination with spaced vertical walls, a retort abutting said walls, comprising a plurality of course of brick laid in planes transverse to an axis through the center of said retort, said bricks having vertical planes of contact between each of the bricks and bricks contiguous thereto, the planes of contact of certain of the bricks on two opposite sides of each brick converging towards 120 the exterior of said retort.

4. In combination with opposite spaced walls, opposite tile members abutting said walls, a retort disposed between and abutting said tile members comprising courses of brick 125 laid in planes transverse to said walls having vertical planes of contact between each of the bricks and bricks contiguous thereto with certain of the bricks in each course disposed against said tile members, the vertical planes 130

of contact of the remaining bricks having opposed sides of each brick in each course converging towards the exterior of said retort.

5. In combination with opposed vertical walls, opposite tile members abutting said walls, a retort abutting said tile members, said retort comprising courses of brick laid in planes transverse to said walls having vertical plane of contact between each of the 10 bricks and bricks contiguous thereto, the vertical planes of contact of certain of the bricks having two opposed sides of each brick in each course converging towards the exterior of said retort.

15. In combination with opposed vertical walls, a retort, opposite vertical wall tiles abutting said walls, said tiles having faces abutting the retort converging towards the walls, said retort comprising a plurality of 20 substantially elliptical courses of brick laid in planes transverse to said tiles, said bricks having vertical plane of contact between each of the bricks and bricks contiguous thereto, the end bricks in each course contacting with 25 said converged faces, the vertical planes of contact of the remaining bricks having two opposed sides of each brick in each course converging towards the exterior of said retort.

30. 7. In combination with opposed vertical walls, a retort abutting said walls comprising a plurality of courses of brick laid in planes transverse to the vertical axis of the retort, said bricks having vertical plane of 35 contact between each of the bricks and bricks contiguous thereto, the vertical planes of contact of certain of the bricks in each course converging towards the exterior of the retort, certain of the bricks in each course being provided with a recess to increase the 40 lightness and heat conductivity of the brick.

8. In combination with opposed vertical walls, a vertical retort abutting said walls comprising a plurality of courses of brick laid in planes transverse to the vertical axis 45 of the retort, said bricks having vertical planes of contact between each of the bricks and bricks contiguous thereto, the vertical planes of contact of certain of the bricks in successive series of courses converging towards the exterior of the retort, and the planes of contact of certain of the bricks in a course beneath the series converging towards the interior of said retort.

55. 9. In combination, opposed vertical wall members, opposite tile members abutting the opposing faces of said wall members and being provided with a pair of abutment faces slightly inwardly converging towards said 60 wall members, a retort between said tile members comprising transverse courses of brick including end bricks disposed against said abutment faces, each alternate course comprising a central end brick having inclined meeting faces lying flat against said

abutment faces and corner bricks adjacent to said central brick and having flat faces contacting and extending to the outer side edges of said abutment faces; the intervening courses comprising corner brick having flat faces extending to said edges; the side brick of the courses being disposed end-for-end to provide abutment faces.

Signed at New York in the county of New York and State of New York this 20 day of 75 September A. D. 1927.
